DRINKING WATER DISPENSER

Austin Gudmundsen, Wauwatosa, Wis., assignor
of one-half to Rudolph L. Hasche, Milwaukee,
Wis.

Application September 3, 1932, Serial No. 631,600

12 Claims. (Cl. 62—142)

The invention relates to devices for containing and dispensing drinking water.

According to the invention a container is provided to which drinking water is supplied in the form of pure water ice. Suitable devices, preferably an electric heater, may be provided to melt the ice to obtain water therefrom. If desired, a warm water reservoir may be associated with the container supplied with water obtained by melting the ice.

A suitable dispensing button may be provided for dispensing the water. If desired, suitable mixing devices may be provided for mixing the warm water and the cold water obtained directly from the melting ice to secure a drink of the desired temperature.

According to the invention, an automatic governing device may be provided for maintaining a predetermined amount of water in liquid form in the container and suitable safety devices may be provided for preventing burning out of the heater when all the ice has been consumed.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which

35 Fig. 1 represents a front view of the dispenser; Fig. 2 is a side view with parts broken away; Fig. 3 is a section on the line 3—3 of Fig. 4; Fig. 4 is a section on the line 4—4 of Fig. 3; Fig. 5 is a section on the line 5—5 of Fig. 4;

40 Fig. 6 is a detail illustrating the dispensing and mixing mechanism; and

Fig. 7 illustrates a block of ice for supplying the drinking water.

45 In the following description and in the claims, various details will be identified by specific names for convenience, but they are intended to be as generic in their application as the art will permit.

Like reference characters denote like parts in the several figures of the drawings.

50 In the drawings accompanying and forming part of this specification, certain specific disclosure of the invention is made for purposes of explanation, but it will be understood that the 55 details may be modified in various respects with-

out departure from the broad aspect of the invention.

Referring now to the drawings, the drinking water dispenser comprises a body having an upper ice holding chamber, indicated by 10, and a lower casing, indicated by 55. The ice chamber 10 has walls of suitable heat insulating material and its construction will be obvious to those skilled in the refrigerator art. The chamber 10 may be provided with a top lid 15 suitably hinged thereto for charging the chamber with ice.

If desired, a perforated bottom plate 11 may be provided upon which the block of ice 14 may rest. Located under the bottom plate 11 may be a second bottom plate 12 supporting a suitable electric heater 13 which may be in the form of a coil, as indicated. The bottom plate 11 may be omitted and the ice cake 14 may rest directly on the heating coil 13, in some instances.

The block of ice 14 may be made of pure drinking water and may be of such size as to keep the container supplied with water say, for instance, a day. These blocks may come wrapped up in a suitable wrapping for sanitary reasons and, if desired, may have a bottom groove 114. 20 A suitable strand of cord, indicated by 115 (Fig. 7), may be wound around the cake passing through the groove 114, as indicated. When the wrapping (not shown) is removed from the cake, the strand 115 permits easy handling of the 25 cake so it may be placed within the chamber 10. After the cake is placed in the dispenser, the strand 115 may be untied, the groove 114 permitting easy removal.

35 The heater 13 may be of any suitable construction well known in the electrical art. In the form shown, it may be made up of a supply conductor and a return conductor running parallel the entire length of the spiral, both conductors being encased in a suitable sheath. These conductors may pass out of the dispenser through a suitable conduit 21, these conductors being indicated by 19 and 20 (see especially Fig. 5).

40 For controlling the electricity supplied to the heater 13, a mercury switch 16 may be provided. This mercury switch may be of well known construction comprising a glass tube containing a pair of contacts in one end and the supply of mercury.

45 The lead wire supplying the electric power to the dispenser is indicated by 18 and supplies a connector 17 from which one wire is connected directly to the wire 20, while the other wire, indicated by 120, is connected to the switch 16. The 50 55

other heater wire 19 is connected directly to the switch 16.

The switch 16 is mounted upon a pivot 22 to which an arm 23 is connected. Operating rod 5 24 connects arm 23 and a float lever 25 which is pivoted to plate 12 at 27. Ball float 26 is connected to lever 25 and is operated by the water collected in the reservoir 112 under supply plate 12.

10 To prevent burning out the heater when all ice is consumed, a safety device is provided. This comprises a button 28 connected to a rod 29 which supports a ring 31 under the ball float 26. A spring 30 normally urges button 28 upwardly so that, as soon as the weight of ice is removed, it will move upwardly, lifting the ball float 26 and opening the switch 16.

15 It will be noted that the switch 16, operating mechanism and wiring connected thereto, together with the ball float, controlling apparatus, safety device and heater are all removable as a unit for cleaning and inspection purposes.

Disposed below the chamber 10 and within the casing 55 is a warm water reservoir 32 (Fig. 2). 20 The reservoir 32 may have suitable vertical fins 33 for increasing its surface so that the water therein may be warmed by the heat of the room, it being understood that the warm room air is free to pass within the casing 55 along the ribs 30 33. A pipe 34 connects cold water reservoir 112 with warm water reservoir 32 and, if desired, this pipe may be covered with heat insulating material 35.

35 For dispensing the water, a dispensing arrangement, shown best in Fig. 6, is provided. The dispensing arrangement is made up of a fitting 60 having a chamber 37 connected to cold water reservoir 112 by pipe 38. The fitting has a second chamber 40 connected to warm water reservoir 40 32 by pipe 39.

40 The fitting 60 also has a mixing chamber 61 provided with an outlet spout 41. The walls of the chambers 37 and 40 are provided with valve seats communicating with the mixing chamber 45 61. Resting on these conical valve seats are conical valve discs 42 and 43.

Connected with the valve discs 42 and 43 are spindles 44 and 45 passing out through the walls of the mixing chamber 61. Springs 46 and 47, 50 operating between abutments on rods 44 and 45 and the wall of the mixing chamber 61, operate to normally hold the valves 42 and 43 closed.

On the outside of the dispenser is a casing 52 having an outlet 53 adjacent the spout 41. Disposed in a hole in casing 52 is a dial push button 49 having an inclined swash plate 51 adapted to engage spindles 44 and 45. The push button 49 is normally held in its outer position by a spring 50 within a hole in the push button operating 60 against a spindle 48 secured to the wall of mixing chamber 61.

If desired, the lower casing 55 may support a waste receptacle 54 for receiving wasted water. This waste receptacle may conveniently be provided with a bottom outlet valve by which it may be emptied from time to time.

It is thought that the operation of the above apparatus will be obvious from the description given above. When the chamber 10 is charged 70 with ice 14, the weight thereof places the safety ring 31 in its lowermost position, allowing the ball float 26 freedom to operate. The casing walls are well insulated so that the ice melts very slowly. The cold water in reservoir 112 75 must keep a predetermined height or the ball

float 26 drops, closing switch 16, causing the heater 13 to heat up and melt sufficient ice to bring the water level in reservoir 112 up to its predetermined point.

This water also fills the warm water reservoir 5 32 which is kept warm by the air circulation from the room. When the ice is consumed, the safety device is allowed to move upwardly, the ring 31 engaging the float 26, holding the switch 16 in open position thereby preventing the burning out 10 of the heater or waste of heat.

To obtain a drink from the dispenser it is only necessary to push in the button 49. The swash plate 51 engages spindles 44 and 45 in a manner depending upon the rotary position of the dial 15 push button 49.

As shown in Fig. 1, the casing 52 is marked with temperature indications and the push button 49 is marked with an arrow. By turning push button 49 to the desired temperature, the valves 42 and 20 43 are opened such a distance as to supply the proper proportion of water of each temperature to give a drink of the desired temperature.

When the dial push button 49 is turned all the way in one direction to the temperature of 35°, 25 no warm water will be obtained by operation of the push button. Similarly, when the dial indicates 65°, no cold water will be obtained by operating the push button. These are the extreme positions and the swash plate 51 is so arranged 30 that operation of the push button only opens the one valve under these extreme conditions.

It is obvious that the invention has many advantages. To supply drinking water containers it is only necessary to supply a block of pure water 35 ice. The troublesome bottles of drinking water used in the prior art are unnecessary. The dispensing push button arrangement permits a nice control of the temperature of the drinking water dispensed. Persons desiring somewhat warm 40 drinking water may have it and persons desiring quite cold drinking water may also obtain it.

The electric current necessary to melt the ice will obviously be comparatively small. Furthermore, there are no packed outlets and all operating parts are of simple construction. The position of the electric switch and the extending 45 of the operating apparatus to the top of the ice chamber does away with any possibility of leakage of water.

The unit construction of heating coil, perforated plates, float, conduit, rod, linkage and entire switch box permits easy removal from the ice chamber for cleaning and inspection and repair purposes.

While certain novel features of the invention have been disclosed and are pointed out in the annexed claims, it will be understood that various omissions, substitutions and changes may be made by those skilled in the art without departing from 60 the spirit of the invention.

What is claimed is:

1. In a drinking water apparatus a chamber adapted to hold a block of ice as a source of drinking water, an electric heater associated therewith, 65 a switch for controlling said heater, a reservoir for receiving the water obtained by melting the ice and a control arrangement in said reservoir for turning off said switch after a predetermined amount of water has been melted.

2. In combination, a chamber adapted to hold a block of ice, a heater associated therewith, a switch for controlling said heater, a reservoir for receiving the water obtained by melting the ice, 70 a float arrangement in said reservoir for turning 75

off said switch after a predetermined amount of water has been melted, and a safety device for turning off said switch when the ice has been consumed.

5. 3. In combination, a chamber adapted to hold a block of ice, a heater in the bottom of said chamber, a switch for controlling said heater, a reservoir under said heater for receiving the water obtained by melting the ice, a control arrangement comprising a float in said reservoir and linkage connecting said float and said switch for turning off said switch after a predetermined amount of water has been melted, and a safety device comprising a spring pressed member on 10 which the block of ice rests and another member engageable with said control arrangement for turning off said switch when the ice has been consumed.

4. A drinking water dispenser comprising a source of drinking water in the form of ice, an electrical heater, means for energizing said heater for melting said ice, a container for holding cold water obtained from said ice, a second container for holding warmer water also obtained from 25 said ice, and dispensing apparatus for mixing and dispensing water from said containers.

5. A drinking water dispenser comprising a source of drinking water in the form of ice, means for melting said ice, a container for holding cold 30 water obtained from said ice, a second container for holding water obtained from said ice, which has been warmed, and dispensing apparatus for mixing and dispensing water from said containers.

35. 6. In a combined dispensing and mixing apparatus, a source of a first substance, a source of a second substance, separate valves for controlling the supply of said substances, a single operating member operating said valves, and means whereby movement of said member in one 40 direction controls the relative amount of opening of said valves and movement of said member in another direction dispenses said substances.

7. In a combined dispensing and mixing apparatus, a source of a first substance, a source 45 of a second substance, separate push valves for controlling the supply of said substances, a push button operating said push valves, said button having a swash plate whereby the rotative position of said button controls the relative amount 50 of opening movement of said valves caused by pushing said push button.

8. In combined mixing and dispensing apparatus, a source of cold water, a source of

warmer water, first and second chambers supplied by said sources respectively, said chambers having first and second valve seats respectively, said valve seats communicating with a mixing chamber having an outlet, first and second valve discs on said seats, spring means normally holding said valve discs on their seats, an outer casing having an outlet adjacent said spout, a push button passing through said casing and having a swash plate at an angle thereto, and spring 5 means normally holding said push button in outer position.

9. In combined mixing and dispensing apparatus, a source of cold water, a source of warmer water, first and second chambers supplied by said sources respectively, said chambers having first and second valve seats respectively, said valve seats communicating with a mixing chamber, a spout connected to said mixing chamber, first and second valve discs on said seats, 20 spindles connected to said valves and passing through a wall of said mixing chamber, abutments on said spindles, springs between said abutments and said wall, an outer casing having an outlet adjacent said spout, a push button passing 25 through said casing and having a swash plate at an angle thereto, a pin secured to said wall, said button having an opening receiving said pin and a spring between the bottom of said opening and 30 said pin.

10. A drinking water dispenser comprising a container for holding a source of drinking water in the form of ice, an electrical heater for melting said ice to provide drinking water, a container for holding said water, a dispensing device 35 for dispensing said water, and means governed by the operation of said dispensing device for controlling the electrical energy impressed on said heater.

11. A water dispenser comprising a container 40 for holding a source of water in the form of ice, a heating device for supplying heat to melt said ice to provide water, a dispensing device for dispensing said water, and means governed by the operation of said dispensing device for controlling 45 the heat supplied by said heating device.

12. A water dispenser comprising a container having a part adapted to hold water ice, a second part for holding the water obtained from the melting ice, said water being in close thermal contact with said ice, a dispensing device, and means governed by the amount of said water for controlling the supply of heat to melt said ice. 50

AUSTIN GUDMUNDSEN.
